UNITED STATES PATENT OFFICE

EDMOND J. LONERGAN, OF CHICAGO, ILLINOIS.

COIN-OPERATED ATTACHMENT FOR PAY-TELEPHONES.

No. 895,777.

Specification of Letters Patent. Patented Aug. 11, 1903.

Application filed February 19, 1903. Serial No. 416,659.

To all whom it may concern:

Be it known that I, EDMOND J. LONERGAN, a citizen of the United States, residing at Chicago, in the county of Cook and State of Illinois, have invented a new and useful Improvement in Coin-Operated Attachments for Pay-Telephones, of which the following is a specification.

My invention relates to improvements in the attachment, commonly employed on pay-telephones, which is adapted to be reduced to operative condition by the interposition of the coin to afford an abutment through which to transmit the motion of the operating lever for working the mechanism to perform its signaling function preparatory to releasing the coin to permit it to drop into the receptacle provided to receive it.

Referring to the accompanying drawings— Figure 1 shows my improved attachment by a view in side elevation in its casing represented by a section taken at the line 1 on Fig. 7, and regarded in the direction of the arrow, the parts of the mechanism being represented in normal position. Fig. 2 is a section taken at the line 2 on Fig. 6, and viewed in the direction of the arrow; and Fig. 3, a broken section taken at the line 3 on Fig. 2, and viewed in the direction of the arrow. Fig. 4 is a view like that presented in Fig. 1, but showing the parts of the mechanism in the condition they assume by depressing the operating lever to its full extent after a coin has been inserted to afford the abutment. Fig. 5 is a section taken at the line 5 on Fig. 1, and viewed in the direction of the arrow. Fig. 6 shows the mechanism in front elevation by a section taken at the line 6 on Fig. 1, and viewed in the direction of the arrow. Fig. 7 is a section taken at the line 7 on Fig. 2, and viewed in the direction of the arrow.

A suitable construction of the casing for my improved attachment may be that represented, comprising an integral back 8 and base 9 extending at right-angles to each other, the back being adapted to be fastened against the board 10 of an ordinary wall-telephone between the transmitter and shelf of the instrument; and a cast-metal cover 11, forming the casing-sides, the top and the front of desired configuration such as that represented. This last-named casting affords the removable section of the casing adapted to be locked in position by engagement of a suitable key-operated lock formed on the casing-front, as indicated at 12, to engage

with the forward end of a post 13 extending horizontally from the back 8, with which it may form an integral part. However, the construction of the casing and particular locking means therefor are not essential to my invention and need not, therefore, be shown and described in more minute detail.

From the base 9, near the right-hand edge thereof, regarded from the front of the attachment, rises a frame 14. On the upper end of the frame is pivotally supported, at 15, to depend at the outer frame-side, an arm 16 containing a cam-slot 17 adjacent to which is a stop 18; and on the lower end of the arm is formed a segmental ratchet 19, in the path of which is pivoted on the frame-side a pawl 20 under the control of a spiral spring 21 connected with the frame. Another spiral spring 22 connects the arm from its upper end with the frame to return the arm to its normal forward position when turned therefrom by depressing the operating lever 23, which is pivoted at its inner end to the outer side of the arm to engage at that end with the stop 18, the lever projecting beyond the front of the casing through an elongated slot 24 therein and being provided on its outer end with a finger-grasp 25.

A cast plate 26 (Fig. 1), rigidly fastened to the inner side of the frame 14 near its forward edge to extend at a right-angle thereto, has provided in its front side grooves forming the coin-chutes indicated at 28 and 29, in Fig. 6, this plate being covered by a thin face-plate 27 for confining a coin passing through either chute; and laterally elongated openings 30 and 31, serving the purpose hereinafter explained, are provided through these plates in the junction between the two chutes, which form, respectively, a coin-return and coin-feed chute. On the back of the plate 26 is supported an electro-magnet device 32, forming a selective device of well-known construction, commonly used on pay-telephone attachments of the character to which my invention relates, for enabling the operator at the telephone-exchange to direct the course of a coin introduced through an insertion-slot 33 into one or the other of the two coin-chutes. This device involves a pair of parallel magnet-spools 34, 35, on a rigid support 36 extending from the back of the plate 26, the spools being independently included in the circuit of a generator (not shown), with a spring-controlled armature 37 common to both magnets, and pivotally

supported at its upper and lower ends to adapt it to be attracted by either one of the magnets which is energized; the armature having pins 38 and 39, projecting from its 5 face, at opposite sides of its pivotal support, into coincidence with the openings 30 and 31. Each time the lever 23 is depressed to the full extent, after the mechanism has been rendered operative as hereinafter explained 10 by inserting a coin, a counter 40, of the ordinary disk-type, is actuated to register each operation of the device, which is furthermore announced by the sounding of a bell 41, these results being produced by the 15 following-described mechanism: In guides on the outer side of the frame 14 is confined, to reciprocate horizontally, a slide-bar 42, having its ends extending at right-angles to afford a rear stop 43 and a forward stop 44 20 to engage with parts of the frame in their paths, the arm 44 affording one stop carrying a U-shaped member 45 having the horizontally and backwardly extending fingers 46 and 47, with a coin-seating trough 48 extending along the upper side of the finger 46. In horizontal alinement with the finger 46 is reciprocably supported, in a bearing 49 projecting from the inner side of the frame, a plunger-bar 50 terminating at its forward 25 end in a recessed or bifurcated head 51 and carrying in a slot formed in its opposite end a pivoted trip-finger 52 projecting into the path of the stem 53 of the spring-pressed operating-finger 54 for actuating the tongue 30 35 55 of the bell 41. The slide-bar 42 carries on its outer side (Fig. 1) a roller 56 extending into the cam-slot 17 of the arm 16, whereby when the operating lever is released after depression thereof, the resultant turning of 40 the arm under the action of the spring 22 will produce engagement of the cam-slot with the roller to return the slide-bar to its normal forward position. Extending parallel with the slide-bar 42 and guidingly supported on the inner side of the frame to reciprocate longitudinally, is a slide-bar 57 45 having its forward end bent to a right-angle and affording a bearing on which is mounted between its ends a curved chute 58 normally 50 coinciding at its upper end with the discharge-end of the chute 28 and containing in its upper end a vertical slot 59 coinciding with the finger 46, this chute being provided between its ends with a slot 60 registering 55 with the finger 47, and being bifurcated at its lower end to form a slot 61 affording a display opening for the coin, at a point where it is arrested after performing its work, to provide a species of coin-detector; the slot 60 60 being coincident with an opening provided in the front of the casing and covered with glass 62.

Immediately above the chute 58 there is provided in the back-plate of the chute 28 65 an opening containing a rectangular door 63,

hinged at its upper end and maintained normally closed by a spring-connection 64 with the frame, this door serving a purpose hereinafter explained.

The counter 40 has on its operating-shaft 70 a crank-arm 65, connected by a spring 66 with the frame; and this crank-arm is connected from its free end by a bent rod 67 with the plunger-bar 50 near its rear end, whereby each time the plunger-bar is forced 75 backward to ring the bell its connection with the crank-arm of the counter actuates the latter to register the operation of the machine, the spring 66 operating through the crank-arm 65 and the rod 67 to return the 80 plunger-bar to its forward position.

On the base 9 is fastened a box forming the coin-receptacle 68 containing in its upper side an opening 69, shown of rectangular form, covered by a slide-plate 70 reciprocably supported in lateral guides 71 on the under side of the top of the receptacle, this slide-plate containing a transverse slot 72 through which the lower bifurcated ends of the chute 58 project. The box has secured 90 upon its top an arresting-tongue 73 projecting over the forward edge of the opening 69 and through the base of the coin-display slot 61 in the curved chute 58. A longitudinally yielding rod 74 is supported in bearings on the inner side of the frame to register at its forward end with the coin-display slot 61, this rod having a spring connection 75 from its rear bent end with the forward bearing 76 through which it passes.

On the forward end of the box is a door 77 hinged at its lower edge to open outwardly and carrying a key-operated lock, indicated at 78, for fastening it in its closed position. Within the box, on a bracket 79 provided 105 therein, is supported a counter 80 which may be in all particulars like the counter 40. The door 77 carries a hinged spring-trip finger 81 extending into the path of the operating spring-retracted crank-arm 82 on the shaft 110 of the counter, the movement of which is limited by stops 83, 84, on the adjacent end of the counter. By means of this device, each time the door 77 is opened to gain access to the receptacle 78 for removing the 115 coins therefrom, the finger 81 engages the crank 82 to operate the counter and cause it to register the opening of the door, the finger becoming disengaged from the crank-arm in the continued movement of the door 120 in opening, in which the crank-arm encounters the stop 84 to free it and permit its return by the spring 85 to normal position, where it encounters and is arrested by the stop 83.

The operation is as follows: When a user of the telephone equipped with my attachment calls up the operator to attain the desired connection, such user introduces a coin of proper denomination into the insertion- 125 130

slot 33, whence it drops upon and is arrested by the pins 38, 39 on the armature. If the desired connection is not obtainable, the operator will energize the magnet 34 to exert 5 attraction on the armature 37 and thereby withdraw the pin 39 from the opening 31 to free the inserted coin and permit it to discharge through the chute 29 into a cup 86 provided on the front of the casing to communicate with the lower end of that chute, and thus return the coin to the user because of the failure to obtain the desired connection. On the other hand, should the connection be obtainable, the operator will energize 10 the magnet 35 to attract the armature and withdraw the pin 38 from the path of the coin, which will thereupon roll down the chute 28 and lodge in the upper end of the chute 58, wherein it is arrested by a stop-lug 87 (Fig. 7) projecting from the inner side of the frame into the path of the coin through the movable chute 58 in its normal position. At this point the coin registers with the inner end of the finger 46. Thereupon, by depressing 15 the lever to turn the cam-arm 16, its engagement with the roller 56 moves the slide-bar 42 inward, thereby abutting the finger 46 against the coin and binding it against the chute 58 while moving the latter backward, under guidance of the slide-bar 57, and with it the slide-plate 70 to maintain 20 closure of the opening 69, though withdrawing the slot 72 from underneath the tongue 73. Continued depression of the operating lever abuts the coin against the bifurcated end of the plunger-bar 50 to drive the latter backward and engage the trip 52 with the bell-operating handle 53 to sound the bell. The plunger-bar also operates to hold the 25 coin against the end of the finger 46, the coin coming into contact with the end thereof before the coin has been moved off the stop-lug 87. This backward movement of the bar 50 also actuates the rod 67 to turn, through the medium of the crank-arm 65, the shaft of the counter 41 to cause the latter 30 to register the operation.

It will be understood that the pawl 20 by its engagement with the ratchet 19 until just previous to the end of the depression of the operating lever, prevents the return of the latter from any intermediate point in the depression, wherein when the pawl clears the ratchet at the end of the depression, (where 35 the further movement of the arm 16 is arrested by abutment of the forward side of the cam-slot against the roller 15) the action of the spring 22 (on releasing the operating lever) reverses the turning of the cam-arm to engage the cam-slot with the roller and move the slide-bar 42 and parts carried by it to the normal position. It will also be understood that no operation of the attachment ensues 40 from depressing the lever 23 unless a coin is interposed between the arm 46 and plunger- 45

bar 50, since in the absence of the coin this arm enters the bifurcated end of the plunger-bar without abutting against it to effect its movement.

The finger 47, while not an indispensable feature of the construction, will serve to intercept the coin in the event of its becoming prematurely dislodged from its abutment-position in the upper end of the movable coin-chute, and thus prevent it from dropping to the lower display-end of that chute until another coin, which has previously attained the last-named position, shall have been discharged therefrom as hereinafter described.

With the return of the slide-bar 42, the stop 43 on its inner end engages the adjacent end of the slide-bar 57 to drive the latter forward and with it the chute 58 into normal position. The forward movement of the chute 58, at the initial part thereof, releases the coin, which drops in the chute while the transverse slot in the slide-plate 70 is still uncovered by the tongue 73; but until the movable chute has attained its forward position, the rod 74 projects through the slot 71 in the chute-base and thus into the path of the coin to arrest it against dropping through the slot 72 into the coin-receptacle; and while the chute 58 is attaining its normal forward position, its lower slot will clear the end of the rod 74, but then the tongue 73 will overlap the slot in the slide-plate so that the coin, when it is advanced ahead of the end of the rod 74 by the forward movement of the chute, will drop and light upon the tongue, 100 to be retained in display-position, propped by bearing backward against the end of said rod, until the attachment is again operated to retract the chute 58 and withdraw the slot in the slide-plate 70 from the tongue 73 to 105 permit the coin to enter the box 68.

Each operation of the attachment is a repetition of that described, causing the previously inserted coin to be dislodged from its display-position into the coin-receptacle and the last inserted coin to take its place and remain under display until the next operation. Should two coins be inserted in succession without operating the attachment between the insertions and because, for example, of 110 the abnormal thinness of one or both coins they should become wedged by overlapping one another below the discharge-end of the chute 28, in forcing the chute 58 inward the coin in alinement with the finger 46 will be 115 pressed against the lower edge of the upper overlapping coin, thereby forcing the latter against the spring-closed door 63 and opening it to release the surplus coin, which will fall inside the casing, thereby preventing any 120 damage to the mechanism, such as would ensue without the provision of the yielding door.

From the foregoing description of the mechanism, it will be understood that the objects of the invention are reliably accom- 130

plished, these objects being, besides providing a desirable novel construction of mechanism, to cause the attachment to register each operation as also to announce the same, and to cause each opening of the cash-box to be registered, these two registrations being independent of each other in the sense that two different persons with different keys, the one holding the key to the casing and the other a similar key and also one for the lock of the door 77, may be required, respectively, to take the readings of the register 40 and periodically collect the contents of the coin-receptacle. In this way the two registers afford a check from one to the other, on the two persons respectively intrusted with taking the readings from the register 40 and with the collections of the money.

What I claim as new, and desire to secure by Letters Patent, is—

1. In a coin-operated attachment the combination with a coin-feed chute, and a coin-receptacle, of a reciprocable coin-chute normally registering with said feed chute and leading to said receptacle, said receptacle being provided with an opening therein, a slide plate connected to the reciprocable chute and covering the opening; and means for reciprocating said last mentioned chute.
2. In a coin-operated attachment the combination with a coin-feed chute, and a coin-receptacle, of a reciprocable coin-chute normally registering with said feed chute and leading to said receptacle, a reciprocating slide, an opposed yieldingly mounted bar, and means for operating the slide to cause it to engage and hold a coin between it and the yielding bar and in engagement with the reciprocable chute.
3. In a coin-operated attachment the combination with a coin-feed chute, and a coin-receptacle, of a reciprocable coin-chute normally registering with said feed chute and leading to said receptacle, a reciprocating slide, and means in line with the slide and opposed to the movement thereof for holding a coin on said slide in engagement with said reciprocable chute.
4. In a coin-operated attachment for pay-phones, the combination with a coin feed-chute and a coin-receptacle, of a reciprocable coin-chute normally registering with said feed-chute and leading to said receptacle and containing a coin-display opening, an operating lever, and coin-operated connections between said lever and reciprocable chute.
5. In a coin-operated attachment for pay-phones, the combination with a coin-feed chute and a coin-receptacle, of a reciprocable coin-chute containing a coin-display opening in its lower end and normally registering at its opposite end with said feed-chute, an opening in the coin-receptacle having a slotted slide-plate covering it and connected

with the lower end of the reciprocable chute, an operating lever connected with said reciprocable chute, and a tongue on said receptacle extending over the opening therein across the slide-plate slot in its normal position.

6. In a coin-operated attachment for pay-phones, the combination with a casing-enclosed frame, of a coin-feed chute, a slide-bar supported on the frame and carrying a roller and a coin-engaging finger, a spring-retracted arm pivotally supported on the frame and provided with a cam to engage said roller, an operating lever connected with said cam-arm, a coin-chute reciprocably supported on the frame to register normally with said feed-chute and provided with a slot registering with said finger, with a coin-stop extending into the path of the coin in the normal position of the reciprocable chute, and a plunger-bar supported on the frame and having a recessed end registering with said slot, for the purpose set forth.

7. In a coin-operated attachment for pay-phones, the combination with a casing-enclosed frame, of a coin-receptacle having an opening, a slotted slide-plate covering said opening and a tongue on said receptacle extending over the slot in the normal position of the slide-plate, a slide-bar supported on the frame and carrying a roller and a coin-engaging finger, a spring-retracted arm pivotally supported on the frame and provided with a cam to engage said roller, an operating lever connected with said cam-arm, a coin-chute reciprocably supported on the frame to register normally with said feed-chute and provided in its upper end with a slot registering with said finger and at its lower end with a coin-display opening, and engaging at its lower end with said slide-plate, a coin-stop extending into the path of the coin in the normal position of the reciprocable chute, and a plunger-bar supported on the frame and having a recessed end registering with said slot, for the purpose set forth.

8. In a coin-operated attachment for pay-phones, the combination with a casing-enclosed frame, of a coin-feed chute, a slide-bar supported on the frame and carrying a roller and a coin-engaging finger surmounted by a coin-rest, a spring-retracted arm pivotally supported on the frame and provided with a cam to engage said roller, an operating lever connected with said cam-arm, a coin-chute reciprocably supported on the frame to register normally with said feed-chute and to be engaged for retracting it by said slide-bar, and containing a slot in its upper end registering with said finger, a coin-stop extending into the path of the coin in the normal position of the reciprocable chute, and a spring-retracted plunger-bar supported on the frame.

9. In a coin-operated attachment for pay-phones, the combination with a casing-

inclosed frame, of a coin-feed chute, a slide-bar supported on the frame and carrying a roller and a coin-engaging finger, a spring-retracted arm pivotally supported on the 5 frame and provided with a cam to engage said roller, an operating lever connected with said cam-arm, a coin-chute reciprocably supported on the frame to register normally with said frame-chute and to be engaged for re- 10 tracting it by said slide-bar, and containing a slot in its upper end registering with said finger, a coin-stop extending into the path of the coin in the normal position of the reciprocable chute, and a spring-retracted plunger-bar 15 supported on the frame and having a recessed end registering with said slot.

10. In a coin-operated attachment for pay- 20 telephones, the combination with a coin-feed chute and a coin-receptacle, of a reciprocable coin-chute containing a coin-display opening in its lower end and normally registering at its opposite end, containing a slot, with said feed-chute, a coin-stop projecting in the path of the coin in the normal position of the reciprocable chute, a slide-bar supported on the frame and having a finger registering with said slot, a plunger-bar having a recessed end registering with said slot, an operating lever connected with said slide-bar to actuate the reciprocable chute, a coin-receptacle provided with an opening, a slotted slide-plate covering said opening and engaged by the lower end of the reciprocable chute, a tongue extending over said opening to coöperate with the slot in said slide-plate, and a stop-rod registering with said coin-display opening to coöperate therewith, for the purpose set forth.

25

reciprocable chute, and a stop-rod registering 30 with said coin-display opening to coöperate therewith, for the purpose set forth.

11. In a coin-operated attachment for pay- 35 telephones, the combination with a coin-feed chute, of a reciprocable coin-chute containing a coin-display opening in its lower end and normally registering at its opposite end, containing a slot, with said feed-chute, a coin-stop projecting in the path of the coin in the normal position of the reciprocable 40 chute, a slide-bar supported on the frame and having a finger registering with said slot, a plunger-bar having a recessed end registering with said slot, an operating lever connected with said slide-bar to actuate the reciprocable chute, a coin-receptacle provided with an opening, a slotted slide-plate covering said opening and engaged by the lower end of the reciprocable chute, a tongue extending over said opening to coöperate with the slot 50 in said slide-plate, and a stop-rod registering with said coin-display opening to coöperate therewith, for the purpose set forth.

EDMOND J. LONERGAN.

In presence of—

A. U. THORIEN,
R. A. SCHAEFER
